(57) **CLAIM**

The ornamental design for a wallet, as shown and described.

DESCRIPTION

1. Wallet

FIG. 1.1 is a perspective view of a wallet of the claimed design.

FIG. 1.2 is a front view of the wallet shown in FIG. 1.1.

FIG. 1.3 is a back view of the wallet shown in FIG. 1.1.

FIG. 1.4 is a right side view of the wallet shown in FIG. 1.1.

FIG. 1.5 is a left side view of the wallet shown in FIG. 1.1.

FIG. 1.6 is a top plan view of the wallet shown in FIG. 1.1.

FIG. 1.7 is a bottom plan view of the wallet shown in FIG. 1.1.

FIG. 1.8 is an additional perspective view of the wallet shown in FIG. 1.1.

Dotted lines in the images represent seams that are not part of the design and are not claimed.
